UNITED STATES PATENT OFFICE.

ISSABELLA KENNY, OF PALISADES PARK, NEW JERSEY.

DESIGN FOR AN APRON.

SPECIFICATION forming part of Design No. 34,596, dated May 28, 1901.

Application filed April 10, 1901. Serial No. 55,258. Term of patent 7 years.

To all whom it may concern:

Be it known that I, ISSABELLA KENNY, a citizen of the United States, residing at Palisades Park, in the county of Bergen and State 5 of New Jersey, have invented and produced a new and original Design for Aprons, of which the following is a specification, reference being had to the accompanying drawing, forming a part thereof.

In the drawing I have shown a perspective view of the apron embodying my design.

The leading feature of my design for an apron consists of a band at the longitudinal central portion of which appear two V-shaped 15 projections on the under edge of the belt and adjacent to each other, while at each end of the band is a complemental half-shield-shaped

portion with straight meeting edges, the upper edge of the band being continuous with the upper edges of said complemental portions. 20

Having described my invention, what I claim as new, and desire to secure by Letters Patent, is—

The design for an apron, as herein shown 25 and described.

In testimony whereof I have signed my name to this specification in the presence of two subscribing witnesses.

ISSABELLA KENNY.
